[57] CLAIM

The ornamental design for a car care organizer tray, as shown and described.

DESCRIPTION

FIG. 1 is a perspective view of a car care organizer tray, showing my new design;

FIG. 2 is a top view thereof, the bottom is understood to be solid, flat and unornamented;

FIG. 3 is a left side view thereof, the right side being a mirror image thereof;

FIG. 4 is a front view thereof, the back being a mirror image thereof;

FIG. 5 is a perspective view of a second embodiment of a car care organizer tray, showing my new design;

FIG. 6 is a top view thereof, it being understood that the bottom is solid, flat and unornamented;

FIG. 7 is a left side view thereof, the right side being mirror image thereof; and,

FIG. 8 is a front view thereof, the rear of the tray is flat and unornamented.
